UNITED STATES PATENT OFFICE.

CHARLES E. BARRY, OF SCHENECTADY, NEW YORK, ASSIGNOR TO GENERAL ELECTRIC COMPANY, A CORPORATION OF NEW YORK.

REGULATION OF DYNAMO-ELECTRIC MACHINES.

No. 884,555.

Specification of Letters Patent.

Patented April 14, 1908.

Application filed September 20, 1905. Serial No. 279,277.

To all whom it may concern:

Be it known that I, CHARLES E. BARRY, a citizen of the United States, residing at Schenectady, county of Schenectady, State of New York, have invented certain new and useful Improvements in Regulation of Dynamo-Electric Machines, of which the following is a specification.

My present invention is applicable more especially to the regulation of those dynamo machines which are driven at speeds which may widely vary, as for example, the generators driven from the car axles of railway trains.

15 In carrying my invention into practice I provide means for automatically decreasing the excitation of the generator as its speed increases. I limit the maximum voltage of the machine, no matter what its speed, and 20 irrespective of the amount of current flowing to the load circuit.

The features of novelty which characterize my invention are pointed out with particularity in the appended claims.

25 The invention itself will be better understood by reference to the following description taken in connection with the accompanying drawings, which represent diagrammatically one embodiment of my invention.

30 Inasmuch as my invention provides means for limiting the maximum voltage of the generator irrespective of its speed and load, I find it particularly applicable to systems such as that shown in the patent to Buttner, No. 35 734,298, July 21, 1903, in which the voltage of the generator is allowed to vary while the voltage at the translating devices is maintained practically constant by the interposition of devices which consume the surplus

40 voltage. The devices employed by Buttner consist of iron wire resistances which, upon any tendency to increase of current, increase in resistance and thereby maintain approximately constant voltage at the translating devices. According to my invention, I limit the voltage of the generator so that no matter how fast the generator may be driven the 45 excess voltage to be consumed in the iron wire resistance of the load never exceeds a 50 moderate amount.

In the drawings, the armature of the generator to be regulated is indicated at 1. The main field winding is indicated conventionally at 2. An auxiliary bucking or differential winding is shown at 3. This winding is

arranged to be supplied with a voltage which varies at a greater rate than the variation in speed of driving. To this end, it is connected across a resistance such as 4 having a high positive temperature - resistance coefficient. 60 This resistance may consist of iron wire. In connecting up the resistance 4, it may if desired be connected directly across the armature 1, though I find it convenient to connect it, as shown in series with the winding 2. In 65 case it is connected across the armature 1, it is, of course evident that a resistance of constant value must be connected in series with it. By connecting the resistance 4 in series with the winding 2, however, this extra resistance becomes unnecessary.

The load for the generator may, of course, be of any desired character but it is indicated here as consisting of a number of lamps, 5, 6, 7 and 8, having in series therewith iron wire 75 resistances, 9, 10, 11 and 12, respectively, the purposes of which have already been indicated. If desired, a storage battery as 13 may be connected across the generator mains to supply current to the load when the voltage of the generator becomes too low and to receive current from the generator at other times. An electrolytic cell 14 consisting, for example, of aluminium plates in a suitable solution may be placed in series with a circuit between the generator and the storage battery 13, which aluminium cell permits passage of current from the generator to the load but prevents the storage battery from discharging backward through the generator at 90 times when the voltage of the generator is below normal.

With the use of an ordinary generator in a system such as described in the Buttner patent, the voltage may in some cases rise 95 excessively above normal and thereby become so great that the iron wire resistances are incapable of preserving the desired constancy of voltage at the load. In accordance with my invention, however, any excessive speed of the generator which tends to increase the voltage is met in the first place by an increase in the resistance of the iron wire resistance 4. This tends to keep down the current in the winding 2. Moreover, as the resistance 4 increases in value much more than the resistance of the winding 3, the division of current between the resistances 4 and winding 3 is altered so that the winding carries an increased proportion 100 105 110

of the total current. Thus, the effect of any small change of voltage of the generator is met by a multiplied demagnetizing effect on the generator field by reason of the presence 5 of the iron resistance 4. The maximum variation of voltage is thus rendered small.

It is obvious that numerous changes may be made in the embodiment of my invention without departing from the spirit thereof, 10 for which reason I do not wish to be limited to the exact details shown and described. Thus, by way of example, I have mentioned the use of an iron wire resistance but it is obvious that resistances of any other suitable material having the same effect may be 15 substituted.

What I claim as new, and desire to secure by Letters Patent of the United States, is,—

1. In a self exciting dynamo electric 20 machine, a main field winding, an opposing field winding, and means responsive to increase in voltage of said machine for causing a more than proportional increase in current in said opposing winding.

2. The combination in a dynamo-electric 25 machine, of an armature, a main field winding supplied with current from said armature, a resistance in series therewith having a high positive temperature-resistance coefficient, and an opposing winding in shunt 30 to said resistance.

3. The combination of a dynamo electric machine, a main field winding, an iron resistance in series therewith, and an opposing field winding in shunt to said resistance. 35

4. In a dynamo-electric machine, the combination of an armature, two field windings therefor, and means for causing current in one winding to vary in a proportion greater and in the other winding in a proportion less 40 than the variation of voltage of the generator.

In witness whereof I have hereunto set my hand this 18th day of September, 1905.

CHARLES E. BARRY.
